UNITED STATES PATENT OFFICE.

WILLIAM CALHOUN, OF NEW YORK, N. Y., ASSIGNOR, BY MESNE ASSIGNMENTS, TO NATIONAL TELEPHONE LOCK COMPANY, A CORPORATION OF THE DISTRICT OF COLUMBIA.

COIN-OPERATED TELEPHONE-LOCKING DEVICE.

SPECIFICATION forming part of Letters Patent No. 784,546, dated March 14, 1905.

Application filed September 18, 1903. Serial No. 173,665.

To all whom it may concern:

Be it known that I, WILLIAM CALHOUN, a citizen of the United States, residing in the city and county of New York, State of New York, have invented a new and useful Improvement in Coin-Operated Telephone-Locking Devices, of which the following is a full and exact specification.

My invention consists of a coin-operated device in which by means of an adjustable mechanism a telephone-receiver is restrained from operation, except by the intervention as a part of a releasing device of a coin or disk of metal introduced into the restraining device and made a feature of its operation. I desire to distinguish my invention from devices having an electrical operation.

My invention is essentially mechanical and relates only to the external mechanism of a telephone. So far as its own operation is concerned it will work equally well whether the telephone is in connection or out of it.

To further illustrate my invention, I refer to the accompanying drawings, in all figures of which similar letters represent like parts.

Figure 1 shows my device attached to a telephone-stand, a portion being cut away to show a vertical longitudinal section. Fig. 2 shows an end view; Fig. 3, a plan view, and Fig. 4 illustrates the method of applying my device to a wall instrument.

As shown in the drawings, my invention consists of a device intended to be fastened upon a telephone in such a way that a lever-arm of my device will be secured to the receiver-supporting arm of the telephone and will when in its locked position restrain the telephone-arm from rising. It will be remembered that in the usual forms of the telephone the receiver is hung upon an arm which is brought down by the weight of the receiver so that the electrical circuit is broken and no use can be made of the instrument. The purpose of suspending the receiver from the arm is to use its weight in causing the circuit to be broken. If the arm be retained in its lowest position by any means other than the re-

ceiver, the result is the same, and conversation through the instrument is impossible.

By my device the circuit-making arm of the telephone is restrained in place though the receiver may be removed, and it is only by the operation of my device that the circuit-making arm can be allowed to rise so as to make the circuit.

55

In the drawings, *a* is the telephone-stand; *b*, the receiver.

c is the face-plate of my device.

d is a clamp which by means of a screw fastens my device to the standard of the telephone, in which it is assisted by the clamping-springs *e*, which also grasp the standard. The arm-lever *g*, which projects through a slot at the side of my device, is firmly fastened at *g'* to the arm of the telephone *f*, which I will call the "receiver-arm." The lever-arm *g* is pivoted near its inner end and engages the ratchet of the lever *j*, the upper end of which is acted upon by the spring *j'*.

h is a slot or groove having an opening at 70 the edge of the device.

k is a thumb-piece inserted in the face of the plate *c* and having the arm *k'* rigidly attached to it within the device.

l is a coin box or receiver removably fastened at the lever end of the slot *h* and held in position by the lugs *l'* and *l''*, the former of which rests upon the bottom of the case and the latter on the spring *m*.

n is a coin or metal disk, and *o* and *p* are key-holes in the face of the plate *c*.

q is the side of a wall telephone-desk to which one form of my invention may be applied.

It will be obvious that when my device is fastened upon the standard and the inner end of the lever engages the ratchet *j* the receiver-arm cannot be raised, and consequently the instrument cannot be used. In order to release the receiver-arm and permit it to rise so that the telephone may be used, it is necessary to cause the lower end of the ratchet-lever *j* to disengage from the inner end of the lever-arm *g*. This may be accomplished either

by a key introduced at *o* or by pressure brought against it by the lever *k'* acting upon a metallic disk introduced into the slot *l*, so as to lie against the upper rounded part of the 5 ratchet-lever *j*.

The operation of my invention will be easily understood. When my device is fastened upon a telephone-stand, any person desiring to operate the telephone may either actuate the 10 ratchet-lever with a key at *o* or, having no key, must drop a coin into the slot *h*. This coin will fall upon the ratchet-lever *j*, so that when the thumb-piece *k* is turned it will press against the coin, which, being in contact with 15 the ratchet-lever, will actuate it and disengage the lever-arm *g*, so that the receiver-arm may rise, and the circuit being made the telephone may be used. As soon as the ratchet-lever moves the coin will fall through the slot into 20 the coin-receiver *l*. When it is desired to detach this receptacle, a key introduced at *p* will force back the spring *m* and permit the removal of *l*.

The size and proportions of the mechanism 25 may be varied to adapt it to any size or thickness of coin, and as only one size can be used it will in practice be that which is adapted to be operated by the single coin required

by the local tariff for the use of a public telephone for a local message. The method of 30 attachment shown in Fig. 4 is adapted to the wall-desk receiver-holder. It will always be a matter of ordinary mechanical skill to adjust my invention to varying forms of telephones.

Having thus set forth my invention, what I claim as new, and desire to secure by Letters Patent of the United States, is—

In a coin-operated telephone-locking device, the combination of a lever-arm adapted to be 40 firmly attached to the telephone-receiver arm and to control the motion of the same, a ratchet-lever arranged to act against the inner end of such lever-arm, means for keeping the two in contact, means whereby a movable 45 metal disk may be caused to rest against the upper end of the ratchet-lever and a thumb-piece and lever adapted to press said disk against said ratchet-lever sufficiently to actuate the same, so as to release the receiver-arm, 50 substantially as described.

WILLIAM CALHOUN.
